LATCH CONSTRUCTION MOUNTING MEANS

Gotthard Hagstrom, New Haven, Conn., assignor, by mesne assignments, to The Pioneer Hardware Corporation, Bridgeport, Conn., a corporation of Connecticut

Application June 14, 1946, Serial No. 676,791

6 Claims. (Cl. 292—348)

1

The present invention relates to improvements in latch constructions and relates more particularly to the type of latch construction in which two latch-units are employed, each having means inter-threading with similar means on the other latch-unit, whereby the two said latch-units may be clamped against the respective opposite sides of a door or other closure.

One of the main objects of the present invention is to provide a superior latch construction of the character referred to and having simple, reliable, effective and inconspicuous means whereby one latch-unit may be conveniently turned with respect to the other to effect the clamping of both latch-units in place.

Another object of the present invention is to provide a superior latch construction of the character referred to and having one of the latch-units provided with a wrench-receiving portion and with a cover-member movable into and out of positions wherein it alternately conceals and exposes the said wrench-receiving portion.

With the above and other objects in view, as will appear to those skilled in the art from the present disclosure, this invention includes all features in the said disclosure which are novel over the prior art, and not claimed by me in my pending application Serial No. 665,300 filed April 26, 1946.

In the accompanying drawings, in which certain modes of carrying out the present invention are shown for illustrative purposes:

Fig. 1 is a view of a latch construction embodying the present invention and shown as mounted adjacent the edge of a door, the showing being mainly in plan with the knob, cover-plate, clamping-plate and a portion of one of the coupling-sleeves being in central horizontal section;

Fig. 2 is a transverse sectional view taken on the line 2—2 of Fig. 1 but omitting the door in order to view the inner face of the clamping-plate and associated features, the wrench-receiving notch of the cover-plate being shown in registry with the similar notch of the clamping-plate;

Fig. 3 is a view similar to Fig. 2 but showing the cover-plate as turned to conceal the wrench-receiving notch in the clamping-plate;

Fig. 4 is a broken detail sectional view taken on the line 4—4 of Fig. 3 but on a larger scale;

Fig. 5 is a perspective view of the cover-plate or rose detached and viewing the same mainly from its inner face;

Fig. 6 is a similar view of the assembly comprising the clamping-plate and its coupling-sleeve; and

2

Fig. 7 is a perspective view of a spanner-wrench suitable for use in turning the clamping-plate and the cover-plate or rose.

The particular embodiment chosen for illustration in the accompanying drawings for purposes of making clear a preferred form of the present invention includes a casing 10 adapted to have its inner face seated against the adjacent face of a door or other closure 11 and provided centrally with an externally-threaded rigid coupling-sleeve 12. The said coupling-sleeve projects into the adjacent end of a clearance-passage 13 formed in the door 11, as is indicated in Fig. 1.

Seated against the face of the door opposite the casing 10 is an escutcheon-plate unit generally designated by the reference character 14 and comprising a relatively-thick centrally-apertured clamping-plate 15 and a relatively-thin cup-shaped cover-plate or rose 16.

20 The central portion of the clamping-plate 15 above referred to, is pressed to provide an offset-portion 17 surrounding the aperture in the said clamping-plate and normally seated against the adjacent face of the door 11, as is indicated in

25 Fig. 1. Riveted or otherwise rigidly united with the offset-portion 17 of the clamping-plate 15, is an internally-threaded coupling-sleeve 18 threadedly receiving the externally-threaded coupling-sleeve 12 before referred to. In its outer periphery, the clamping-plate 15 is formed with a wrench-receiving notch 19, for purposes as will hereinafter appear.

30 The cup-shaped cover-plate or rose 16 before referred to has its annular flange 20 extending in an axial direction over the outer periphery of the clamping-plate 15 and provided with a clearance-notch 20a. At its free edge, the flange 20 is formed with four (more or less) retaining-fingers

35 21 which are bent over against the inner face of the clamping-plate 15 to retain the latter and the cover-plate in assembled relationship, while permitting relative rotation to take place when desired, between the said clamping-plate 15 and the cover-plate 16.

40 45 The cover-plate 16, in addition to its flange 20, also includes a face-portion 22 covering the outer face of the clamping-plate 15 and having its center apertured and pressed outwardly to provide an offset-portion 23. Rotatably connected to the offset-portion 23 just referred to, is a knob or other suitable operating-member 24, as is shown in Fig. 1.

50 In order to connect the knob 24 or its equivalent with the cover-plate or rose 16 in such manner as to permit relative rotation, the said knob 24 is

provided with a relatively-slender neck 25. The said neck extends through the aperture in the center of the offset-portion 23 and is burred or riveted over as at 26 against the inner face of a washer 27. The neck 25 also extends through the washer 27 while the latter bears against the inner face of the offset-portion 23 and turns thereon when the knob 24 is rotated.

The knob 24 or other suitable operating-member is, in a manner usual in the art, provided with an axial passage 28 of square or other suitable non-circular form in cross section. The said passage 28 receives the adjacent end of a spindle 29 projecting freely through the coupling-sleeves 12 and 18 as well as through the casing 10, from a lever-handle 30 or other suitable operating-member. The spindle 29 has a cross-sectional form substantially corresponding to the cross-sectional form of the passage 28 in the knob 24 and is rigid with the lever-handle 30. In this manner, the knob 24 and lever-handle 30 are coupled together for concurrent turning movement by the spindle 29 in the event that either the said knob or the said lever-handle is manually turned.

The frictional engagement between the cover-plate 16 and the clamping-plate 15 is greatly in excess of the very slight frictional engagement between the knob 24 and the said cover-plate so that under normal conditions when the knob 24 is turned it will not effect the turning of the cover-plate 16.

Projecting outwardly from the casing 10 is a latch-member 31, as is indicated in Fig. 1. The latch-member 31 or its equivalent may be operated by the spindle 29 in any suitable manner which does not, per se, form a feature of the present invention. One form of operating-means is illustrated in my copending application Serial Number 665,300 previously referred to herein.

In mounting the latch elements upon the door 11 or its equivalent, the unit comprising the casing 10, coupling-sleeve 12, spindle 29, lever-handle 30 and latch-member 31 may be placed against one face of the door with its said coupling-sleeve 12 and spindle 29 projecting into the clearance-passage 13 in the door. The unit comprising the escutcheon-plate unit 14, coupling-sleeve 18 and knob 24 may then have its said coupling-sleeve inserted into the end of the clearance-passage 13 opposite the casing 10 and into threaded engagement with the coupling-sleeve 12. By manually rotating the escutcheon-plate unit 14, the inner face of the clamping-plate 15 and the inner edge of the flange 20 of the cover-plate 16 may be lightly engaged with the adjacent face of the door 11.

Now, by rotating the cover-plate 16 relative to the clamping-plate 15 (if this has not already been accomplished), the clearance-notch 20a in the flange 20 of the said cover-plate may be brought into registry with the wrench-receiving notch 19 in the clamping-plate 15, thereby exposing the said notch 19 in the manner shown in Figs. 1 and 2. Any suitable tool may be inserted into the now-exposed wrench-receiving notch 19 to effect the turning movement of the clamping-plate 15 and hence its coupling-sleeve 18 with respect to the coupling-sleeve 12. In this manner, the inner face of the said clamping-plate may be firmly seated against the adjacent face of the door 11, while at the same time drawing the inner face of the casing 10 into firm seated engagement with the opposite face of the said door.

After the clamping-plate 15 has been tightened,

the cover-plate 16 may be turned with respect thereto sufficiently to bring the clearance-notch 20a in the flange 20 out of registry with the wrench-receiving notch 19 in the said clamping-plate, to thus cause the flange 20 to cover the wrench-receiving notch 19, as is indicated in Fig. 3.

For the purposes of turning the clamping-plate 15 and cover-plate 16, I have found it most convenient to employ a spanner-wrench 33 of the general character illustrated in Fig. 7. The said spanner-wrench 33 is formed at one end with a short arm 34 dimensioned so as to freely extend through the clearance-notch 20a in the flange 20 and into the wrench-receiving notch 19 in the clamping-plate 15, in the manner indicated by broken lines in Fig. 2. Extending outwardly from the arm 34 is a finger 35 sufficiently narrower than the said arm to leave a portion of the end of the latter unencumbered to provide a stop-shoulder 36. The edge of the spanner-wrench adjacent the arm 34 and finger 35 is preferably longitudinally curved as at 37 to substantially conform to the peripheral contour of the flange 20 of the cover-plate 16.

When it is desired to employ the spanner-wrench 33 to effect the tightening of the clamping-plate 15, the arm 34 of the said spanner-wrench may be passed through the clearance-notch 20a in the cover-plate 16 and entered into the wrench-receiving notch 19 of the said clamping-plate, as is indicated by broken lines in Fig. 2.

Now, after the clamping-plate 15 has been sufficiently tightened by means of the spanner-wrench 33 and it is desired to turn the cover-plate 16 with respect to the said clamping-plate, the finger 35 may be entered into the clearance-notch 20a in the flange 20, as is indicated by broken lines in Fig. 3. Under these conditions, the stop-shoulder 36 will limit the penetration of the finger 35 and will not permit the same to extend into the wrench-receiving notch 19, since the said finger is of a length (measured from the stop-shoulder 36) substantially corresponding to the thickness of the flange 20.

When it is desired to demount the latch assembly, the procedures above referred to may be reversed.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A latch construction, including in combination: a first latch-unit designed and adapted for engagement with one face of a door and provided with a threaded portion having its axis extending in a direction transverse of such door; and a second latch-unit designed and adapted for engagement with the opposite face of the door from the said first latch-unit and provided with a threaded portion threadedly engageable with the threaded portion of the said first latch-unit and jointly therewith providing coupling-means to couple the two latch-units together; one of the said latch-units including a clamping-member rigid with its said threaded portion and formed with a wrench-receiving recess constructed and arranged to receive a tool whereby the clamping-member and its rigid threaded portion may be

turned with respect to the threaded portion of the other latch-unit to clamp a door between the two said latch-units, and a cover-member covering the outer face of the said clamping-member and formed with a clearance-opening located so as to be movable into and out of registry with the wrench-receiving recess of the clamping-member, the said cover-member being rotatable with respect to the said clamping-member to move its clearance-opening into and out of registry with the wrench-receiving recess in the clamping-member.

2. A latch construction, including in combination: a first latch-unit designed and adapted for engagement with one face of a door and provided with a threaded portion having its axis extending in a direction transverse of such door; and a second latch-unit designed and adapted for engagement with the opposite face of the door from the said first latch-unit and provided with a threaded portion threadedly engageable with the threaded portion of the said first latch-unit and jointly therewith providing coupling-means to couple the two latch-units together; one of the said latch-units including a clamping-plate rigid with its said threaded portion and formed in its periphery with a wrench-receiving notch constructed and arranged to receive a tool whereby the clamping-plate and its rigid threaded portion may be turned with respect to the threaded portion of the other latch-unit to clamp a door between the two said latch-units, and a cover-plate covering the outer face of the said clamping-plate and formed in its periphery with a clearance-opening located so as to be movable into and out of registry with the wrench-receiving notch in the said clamping-plate, the said cover-plate being rotatable with respect to the said clamping-plate to move its clearance-opening into and out of registry with the wrench-receiving notch in the said clamping-plate.

3. A latch construction, including in combination: a first latch-unit designed and adapted for engagement with one face of a door and provided with a threaded coupling-sleeve having its axis extending in a direction transverse of such door, the said first latch-unit having an operating-member associated therewith; a second latch-unit designed and adapted for engagement with the opposite face of the door from the said first latch-unit and also provided with a threaded coupling-sleeve threadedly engageable with the coupling-sleeve of the said first latch-unit, the said second latch-unit also having an operating-member associated therewith; one of the said latch-units including a clamping-member rigid with its said coupling-sleeve and formed with a wrench-receiving recess constructed and arranged to receive a tool whereby the clamping-member and its rigid coupling-sleeve may be turned with respect to the coupling-sleeve of the other latch-unit to clamp a door between the two said latch-units, and a cover-member covering the outer face of the said clamping-member and formed with a clearance-opening located so as to be movable into and out of registry with the wrench-receiving recess of the clamping-member, the said cover-member being rotatable with respect to the said clamping-member to move its clearance-opening into and out of registry with the wrench-receiving recess in the said clamping-member; and a spindle extending through both of the said coupling-sleeves and operatively interconnecting the respective operating-members of the two said latch-units.

4. A latch construction, including in combination: a first latch-unit designed and adapted for engagement with one face of a door and provided with a threaded coupling-sleeve having its axis extending in a direction transverse of such door, the said first latch-unit having an operating-member associated therewith; a second latch-unit designed and adapted for engagement with the opposite face of the door from the said first latch-unit and also provided with a threaded coupling-sleeve threadedly engageable with the coupling-sleeve of the said first latch-unit, the said second latch-unit also having an operating-member associated therewith; one of the said latch-units including a clamping-plate rigid with its said coupling-sleeve and formed in its periphery with a wrench-receiving notch constructed and arranged to receive a tool whereby the clamping-plate and its rigid coupling-sleeve may be turned with respect to the coupling-sleeve of the other latch-unit to clamp a door between the two said latch-units, and a cover-plate covering the outer face of the said clamping-plate and formed in its periphery with a clearance-opening located so as to be movable into and out of registry with the wrench-receiving notch in the said clamping-plate, the said cover-plate being rotatable with respect to the said clamping-plate to move its clearance-opening into and out of registry with the wrench-receiving notch in the said clamping-plate; and a spindle extending through both of the said coupling-sleeves and operatively interconnecting the respective operating-members of the two said latch-units.

5. A latch construction, including in combination: a first latch-unit designed and adapted for engagement with one face of a door and provided with a threaded portion having its axis extending in a direction transverse of such door; and a second latch-unit designed and adapted for engagement with the opposite face of the door from the said first latch-unit and provided with a threaded portion threadedly engageable with the threaded portion of the said first latch-unit and jointly therewith providing coupling-means to couple the two latch-units together; one of the said latch-units including a clamping-plate rigid with its said threaded portion and formed in its periphery with a wrench-receiving notch constructed and arranged to receive a tool whereby the clamping-plate and its rigid threaded portion may be turned with respect to the threaded portion of the other latch-unit to clamp a door between the two said latch-units, and a cup-shaped cover-plate covering the outer face of the said clamping-plate and having an annular flange extending over the periphery of the said clamping-plate and terminating in means engaging the inner face of the said clamping-plate, the flange of the said cover-plate being formed with a clearance-opening movable into and out of registry with the wrench-receiving notch in the said clamping-plate, the said cover-plate being rotatable with respect to the said clamping-plate to move its clearance-opening into and out of registry with the wrench-receiving notch in the said clamping-plate.

6. A latch construction, including in combination: a first latch-unit designed and adapted for engagement with one face of a door and provided with a threaded coupling-sleeve having its axis extending in a direction transverse of such door, the said first latch-unit having an operating-member associated therewith; a sec-

ond latch-unit designed and adapted for engagement with the opposite face of the door from the said first latch-unit and also provided with a threaded coupling-sleeve, threadedly engageable with the coupling-sleeve of the said first latch-unit, the said second latch-unit also having an operating-member associated therewith; one of the said latch-units including a clamping-plate rigid with its said coupling-sleeve and formed in its periphery with a wrench-receiving notch constructed and arranged to receive a tool whereby the clamping-plate and its rigid coupling-sleeve may be turned with respect to the coupling-sleeve of the other latch-unit to clamp a door between the two said latch-units; and a cup-shaped cover-plate covering the outer face of the said clamping-plate and having an annular flange extending over the periphery of the said clamping-plate and terminating in means engaging the inner face of the said clamping-plate, the flange of the said cover-plate being

formed with a clearance-opening movable into and out of registry with the wrench-receiving notch in the said clamping-plate, the said cover-plate being rotatable with respect to the said clamping-plate to move its clearance-opening into and out of registry with the wrench-receiving notch in the said clamping-plate; and a spindle extending through both of the said coupling-sleeves and operatively interconnecting the respective operating-members of the two said latch-units.
